ATTORNEY

WITNESS:

UNITED STATES PATENT OFFICE.

CARL HAMPTON SPAIN, OF TEMPE, ARIZONA.

SWITCH.

Application filed February 20, 1925. Serial No. 10,618.

This invention relates to an automatic switch for starters of internal combustion engines, the object of the invention being to provide a magnet for closing the switch of the starter circuit and an automatic relay for controlling the circuit of the magnetic switch.

This invention also consists in certain other features of construction and in the combination and arrangement of the several parts, to be hereinafter fully described, illustrated in the accompanying drawing and specifically pointed out in the appended claims.

15 In describing my invention in detail, reference will be had to the accompanying drawing wherein:—

Figure 1 is a diagrammatic view of the invention with parts in section.

20 Figure 2 is a circuit diagram showing the connections to the various electromagnetic switches.

The magnetic switch for controlling the circuit of the starting motor is shown at A and the relay for controlling the circuit of the magnetic switch is shown at B. The switch A comprises a casing 1 which is preferably threaded to a cap 2 bolted to a plate 3 of non-conducting material, said plate 30 carrying the terminals 4 which are arranged in the circuit of the starter motor. A switch member 5 is arranged in the cap 2 and is adapted to bridge the terminals 4 to close the circuit to the starter motor. A stem 6 is fastened to the member 5 and passes through the bottom of the cap 2 and through a telescopic housing 7, the stem being connected with the movable part of said housing. A spring 8 is arranged in the 40 housing and tends to hold the movable part thereof in its lowest position with the member 5 out of engagement with the terminals. A magnet 9 is arranged in the casing 1 and a rod 10 forms the core or armature of said 45 magnet. When the rod is actuated by current flowing through the magnet its upper end will strike the movable part of the housing 7 and force the same upwardly against the action of the spring 8 and thus 50 cause the switch member 5 to engage the terminals 4 and close the circuit to the starter motor. The upward movement of the rod 10 can be limited by the disc 11 adjustably connected with the lower end of the rod 10 and a set screw 12 passing through the lower end of the casing 1 forms an adjustable rest

for the rod 10 when the magnet is not energized.

The relay B for controlling the circuit of the magnetic switch A comprises a core 13 carried by an insulated plate 14 and having a high resistance shunt coil 15 and a reverse series coil 16 associated therewith. The coil 15 terminates at the terminal 17 which is grounded, as at 18, and the coil 16 is electrically connected with the spring actuated switch arm 19 which has one end pivotally connected to the lower part of a casing 20 which encloses the coils. This switch arm 19 carries a contact 20' which normally engages a stationary contact 21 which is supported by a bracket 22 electrically connected with a terminal 23 carried by the plate 14. This terminal is electrically connected with a magnet 9, as shown at 24, and a conductor 25 connects said terminal 23 with a solenoid 26, said solenoid being connected with the ground terminal 17 by the conductor 27. The core 13 is connected with the battery C by the conductor 28 and a switch 29 may be connected with the conductor. A condenser 30 is connected by a conductor 31 with the terminal of the core 13 and a conductor 32 connects the other side of the condenser with the terminal 23. This condenser will act to prevent sparks occurring at the contacts 20' and 21 when the arm 19 is raised. This arm is raised by the upward movement of the rod 33 which is connected with an iron core 34 slidably arranged in a tube 35 forming the center of the solenoid 26. When this solenoid is energized the rod 33 will be raised and as it strikes the arm 19 it will cause the same to be raised and thus separate the contacts 20' and 21 and break the circuit through the coil 16. Then the coil 15 will cause the core 13 to attract the switch arm 19 and thus hold said arm in raised position after the rod 33 has returned to its original position due to the breakage of the circuit of the solenoid 26. The movement of this rod 33 and its core 34 is controlled by a cup-shaped washer 36 on the lower end of the rod 33 and the needle valve 37 controlling the entrance of air into the lower part of the cylinder 35 through the port 38. By adjusting this needle valve the passage of air into the lower part of the cylinder can be regulated and thus the upward movement of the rod 33 can be controlled, as it is retarded in its upward movement by the limited quantities

of air flowing into the bottom of the cylinder below the valve. This air will pass between the valve and the walls of the cylinder on the downward movement of the parts so that it will not check the lowering of the rod 33.

From the foregoing it will be seen that when the motor is to be started through means of the starter motor it is simply necessary to close the switch 29 when current will flow from the battery through the core 13 and both coils 15 and 16 to ground. As the current passes through the coils in opposite directions the core will not attract the switch arm 19. That part of the current passing through the coil 16 will pass through the arm 19, the contacts 20' and 21, bracket 22 to the terminal 23 where some of it will pass over the connections 24 to the magnet 9, energizing said magnet so as to cause the same to raise the rod 10 and thus raise the switch member 5 to close the circuit of the starter motor. Some of the current will also pass through the conductor 25 to the solenoid 26 causing said solenoid to raise the rod 33 which is retarded in its upward movement not only by the slow entrance of air into the cylinder but also by the voltage drop in the battery due to the starting up of the starter motor. When the motor starts the load is taken from the starter which raises the voltage on the battery so that more current flows to the solenoid 26 and then the rod 33 moves more quickly to a position where it will strike the arm 19 and separate the contacts 20' and 21. This will break the circuit to the solenoid 26 and to the magnet 9 and as no current is flowing through the coil 16 the flow of current through the coil 15 will cause the core 13 to act on the switch arm 19 and thus hold the same raised even though the rod 33 has moved from under the same. The parts will remain in this position until the switch 29 is opened when the circuit to the device will be broken and the switch arm 19 will drop to its original position when the parts will be ready to start up the starter motor upon the closing of the switch 29.

With this invention better contact through the starter circuit can be made with the magnetic switch than can be made with the ordinary foot switch now in use. This will increase the life of the starter switch contacts, it also makes the starter switch auto-

matic in action and only requires the closing of a switch to throw the starter motor into action. By using a separate switch for the invention placed in the ignition circuit between the relay and the ignition switch the automatic feature can be brought into use or cut out as desired. It will permit the use of an ordinary switch installed at some convenient place, for instance, as on the steering column, to operate the starter switch with a greater degree of ease than is possible with the foot switch.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device of the class described including a relay comprising a core, a pair of coils associated with the core, means for causing current to pass through the coils in opposite directions, a normally closed switch in the circuit of one coil, a solenoid in the said circuit and means operated by the solenoid for opening the switch to cause the other coil to hold the switch open.

2. A device of the class described including a relay comprising a core, a pair of coils associated with the core, means for causing current to pass thru the coils in opposite directions, a normally closed switch in the circuit of one coil, a solenoid in said circuit, means operated by the solenoid for opening the switch to cause the other coil to hold the switch open and means for regulating the movement of the solenoid operating means.

3. A device of the class described including a relay comprising a core, a pair of coils associated with the core, means for causing current to pass thru the coils in opposite directions, a normally closed switch in the circuit of one coil, means operated by the solenoid for opening the switch to cause the other coil to hold the switch open, means for regulating the movement of the solenoid operating means and a condenser arranged in the circuit of the coil which is provided with the switch.

In testimony whereof I affix my signature.

CARL HAMPTON SPAIN.
